UNITED STATES PATENT OFFICE.

CHARLES E. WILSON, OF ANDERSON, INDIANA, ASSIGNOR, BY MESNE ASSIGNMENTS,
TO DELCO-REMY CORPORATION, OF DAYTON, OHIO, A CORPORATION OF DELAWARE.

INDUCTION COIL.

Application filed April 17, 1925. Serial No. 23,809.

This invention relates to induction coils especially for ignition apparatus of internal combustion engines.

It is among the objects to reduce cost of manufacture and improve the efficiency of such coils.

In the present invention this object is accomplished by the novel construction of the external magnetic circuit of the coil which requires the assembling of only two pieces of material to form the external magnetic circuit instead of handling of many small pieces as has been the practice heretofore.

Further objects and advantages of the present invention will be apparent from the following description, reference being had to the accompanying drawings, wherein a preferred form of embodiment, of the present invention is clearly shown.

20 In the drawings:

Figs. 1 and 2 are plan and end views respectively of the material used to provide the external portion of the magnetic circuit of an induction coil.

25 Fig. 3 is a sectional view of a coil including the present invention.

The induction coil to which the present invention can be applied comprises a metal case 20 which contains a central core 21 consisting of a bundle of wires resting upon a porcelain base 22 supported by the bottom of the container 20. The core 21 is surrounded by a non-conducting tube 23, a secondary coil 24 and a primary coil 25.

30 The cover of the container 20 comprises a metal piece 26 which supports a non-conducting body 27 and terminals 28 and 29.

The body 27 carries a high tension cable receiving socket 30 attached by a conductor

31 to one end of the secondary coil 24. The other end of the secondary coil 24 and one end of the primary are connected by wire 32

35 with terminal 28 and the other end of the primary 25 is connected by wire 33 with the terminal 29.

40 The external portion of the magnetic circuit which constitutes an embodiment of the present invention is indicated in Fig. 3 by a tube 40 comprising a plurality of layers formed by rolling up a strip of material including separate narrow strips of iron.

45 This material is formed by pasting or gluing a strip of paper or other flexible non-conducting and non-magnetizable material

50 41 to a strip of soft iron suitable for induc-

tion coil work. The paper strip 41 is wider than the metal strip 42 and both side edges of the paper project beyond the side edges of the metal strip. After the paste or glue has dried, the assembled strip of paper and 50 iron is slit as indicated by the lines 43. The slits are parallel and extend beyond the side edges of the iron strip but terminate within the margins of the paper strip. The paper should be sufficiently tough and strong 55 to resist tearing after the slits have been made and sufficiently flexible to permit rolling the assembled material into a tube such as is indicated at 40.

The advantages of the present invention 70 are apparent when it is considered that but two pieces of metal are handled in the formation of the external portion of the magnetic circuit for the induction coil.

Heretofore it has been the practice to assemble 75 between the wall of the container and the coil windings, a large number of pieces of iron wire or narrow strips of iron

in order to provide a magnetic circuit in which eddy current losses would be reduced 80 to the minimum.

By means of the present invention the cost of making coils of this type has been materially reduced on account of the reduction of time and labor in the formation of the external portion of the 85 magnetic circuit of the coil. As the paper strip is relatively thin, and the metal strips are arranged regularly upon the paper, a large number of metal strips can be assembled within the space provided in the 90 container for the magnetic circuit.

While the form of embodiment of the invention as herein disclosed, constitutes a preferred form, it is to be understood that other forms might be adopted, all coming within 95 the scope of the claims which follow.

What I claim is as follows:

1. The method of making material for a tubular magnetic circuit of induction apparatus which comprises attaching a strip of flexible non-conducting, non-magnetizable material to a strip of flexible magnetizable metal which is located within the side margins of the other strip, and in shearing the strips entirely across the metal strip but 100 not entirely across the other strip to provide a plurality of separate strips of metal assembled by the side margins of the non-conducting nonmagnetizable strip.

2. Material for the magnetic circuit of in- 110

duction apparatus consisting of a plurality of separate strips of magnetizable metal secured to a strip of flexible nonmagnetic material in proper, spaced relation, the entire assembly being capable of being formed into a tube.

3. Material for the magnetic circuit of induction apparatus consisting of a plural-

ity of separate strips of magnetizable metal secured to a strip of flexible non-magnetic material in proper, spaced relation, the edges of said material extending beyond the respective edges of the metal strips. 16

In testimony whereof I hereto affix my signature.

CHARLES E. WILSON.
